UNITED STATES PATENT OFFICE.

JOHN Y. BASSELL AND FRED C. BLENKNER, OF COLUMBUS, OHIO.

GUN-SIGHT.

No. 805,771.

Specification of Letters Patent.

Patented Nov. 28, 1905.

Application filed July 11, 1904. Serial No. 215,977.

To all whom it may concern:

Be it known that we, JOHN Y. BASSELL and FRED C. BLENKNER, citizens of the United States, residing at Columbus, in the county 5 of Franklin and State of Ohio, have invented a certain new and useful Improvement in Gun-Sights, of which the following is a specification.

Our invention relates to a new and useful 10 improvement in gun-sights.

The object of the invention, essentially, is to provide a gun-sight so constructed and arranged as to meet the many requirements necessitated by the varying visual needs or 15 desires of different gunners.

A special object of the invention resides in a movable hood whereby all the advantages obtained by a globe, a ring, or an open sight are attainable.

20 Further features of novel combination lie in the hinged reflector and an interchangeable and reversible sight-piece.

Finally, the object of the invention is to provide a device of the character described that 25 will be strong, durable, and efficient, and one in which the parts may be so positioned or adjusted as to produce at pleasure most any form of gun-sight that the gunner may demand.

30 With the above and other objects in view the invention consists of the novel details of construction and operation, a preferable embodiment of which is described in the specification and illustrated in the drawings, where- 35 in—

Figure 1 is a rear elevation of the gun-sight. Fig. 2 is a side elevation. Fig. 3 is a front elevation. Fig. 4 is a top plan view with the sight-piece removed. Fig. 5 is a longitudinal 40 vertical sectional view taken on the line xx of Fig. 1. Fig. 6 is a top plan view showing the sight-piece in place. Fig. 7 is a longitudinal vertical sectional view taken on the line yy of Fig. 1. Fig. 8 is a front elevation of 45 a modified form. Fig. 9 is a rear elevation of the same. Fig. 10 is a side elevation of the modified form. Fig. 11 is a plan view of the same with the sight-piece removed. Fig. 12 is a longitudinal vertical sectional view of 50 the modified form, and Fig. 13 is a detail elevation of one of the sight-pieces.

In the drawings the numeral 1 designates the base, which is suitably formed to be readily secured upon the gun-barrel. The base is 55 formed with upwardly-extending side walls 2, between which extends the concaved recess 3,

which is covered by the circular housing 4, whose inner periphery conforms with the recess 3 to form a perfect circle. The housing 4 extends over the forward portion of the base only and terminates at its rear end flush with the sight-piece groove 5, which extends transversely of the base. A removable and reversible sight-piece 6 is adapted to fit in and completely fill the groove 5, having its 60 outer ends shaped to conform to the contour of the vertical walls 2 and provided with locking-recesses 7, extending upward from its bottom, which engage over the fixed pin 8 and the locking-pin 9. The locking-pin 9 is 65 formed with a shoulder 10, which engages with the spring-latch 11 when the pin is withdrawn to prevent its disengagement from the base. The latch normally engages in an annular recess 12 of the pin to hold the same in 70 its locking position. The sight-piece 6 is formed with inwardly-curved lips 13, which align with the longitudinally-extending guides 14 of the walls 2. The guides 14 are so arranged as to form ways into which project 75 the laterally-extending feet 15 of the slideable hood 16. The hood 16 is formed to fit the outer contour of the housing 4 and to completely fill the space between the said housing and the guides 14. The hood is formed with 80 a downwardly-extending angular flange 17, which impinges the rear end of the housing 4 when the hood is in its forward position, thus providing a guard which prevents the disengagement of the hood from the housing. 85 The outer surface of the hood is roughened, as shown at 18, to provide a gripping-surface whereby the hood may be readily moved backward and forward in the guides 14 and the lips 13 to form either a ring-sight or a globe- 90 sight. Guard-plates 19, secured to the rear face of the base by screws 20, cover the rear ends of the guides 14, thus acting as stops to limit the rearward movement of the hood. It will be readily seen that by moving the 95 hood rearward, as shown in Fig. 5, what is known as a "globe-sight" is produced and that by sliding the said hood either forward or backward globes of various lengths may be had and that the amount of light admitted 100 upon the sight-piece is modulated. When the hood is moved to its forward position, as clearly shown in Figs. 2 and 4, the sight-piece is entirely exposed to the light, and all the effects of what is known as a "ring-sight" are 105 obtained. It is to be observed that by simply withdrawing the locking-pin 9 the sight- 110

5.3
piece 6 may be lifted out of the groove 5, reversed, again inserted in the said groove, and the pin shoved forward, thus locking it in place, and a different sight point or center being presented to the eye, as each sight-piece may be designed with different forms of sight-centers on opposite sides, as clearly illustrated in Fig. 5, and by manipulating the hood 16 various light effects may be produced at the pleasure of the gunner and to suit the various climatic conditions. In order to assist in the lighting of the sight-center, we arrange upon the rear end of the base a reflector 21, which has its back concaved to fit the contour 15 of the recess 3, and thus when in its folded position presents no obstruction to the vision of the gunner. This reflector is formed with a flat face 22, which is polished or coated with a reflecting material, so as to readily reflect 20 the light and illuminate the sight-center 23 of the sight-piece 6, which is preferably polished or set with a jewel or brilliant material, such as gold and silver, which when illuminated by the rays of light directed upon it by the reflector becomes luminous. This sight-center 25 is preferably arranged at an angle, so as to readily receive the reflected rays, and when the sight-center 23 is concaved it will tend to gather the rays of light cast upon it by the reflector. It is to be understood, however, 30 that various forms of sight-pieces may be employed with the reflector, which acts to give to the sight-center it true color value, which is destroyed where light is excluded. The reflector is pivotally mounted upon a pin 24, 35 which is supported by hinge-lugs 25, projecting from the base 1, and is also provided with notches 26, in which the head of a spring-pressed plunger 27, arranged in a recess 28 of the base, engages. The notches are so disposed that they engage with the plunger-head 27 when the reflector is in its extended position, as shown in Fig. 5, and when it is in its closed position, as shown in Fig. 4. It will 40 thus be seen that an accidental opening or closing of the reflector which might result from the recoil of the gun is obviated and that the said reflector is maintained in the desired position.

50. In Figs. 8 to 12, inclusive, we have shown a slightly-modified form of sight, in which the housing 4 is omitted, as well as the guard-flange 17 and the hood 29 slightly elongated. In the modified construction the forward portion 55 of the base 1 is slightly elongated, so as to accommodate the lengthened hood. The base 1 is formed with a recess 3^a, like the recess 3, but having less depth than the said recess. The hood 29 has its inner periphery 60 conforming to the contour of the recess 3^a, so as to form therewith a perfect circle. The hood is formed with angular laterally-extending feet 31, which fit in the guideways of the guides 32, which extend longitudinally of the 65 base.

For the purpose of making the hood 29 removable, so that what is known as an "open" sight may be had we provide in the front wall of the base notched headed screws 33, which are so disposed as when turned, as shown in Fig. 8, to abut stop-pins 34 and stand in the path of the feet 31, thereby constituting stops for preventing the accidental displacement of the hood from the guides. However, when it is desired to entirely remove the hood the 75 screws are given a quarter-turn, which causes their notched portions to lie under the ways of the guides 32, thereby unobstructing the same and allowing the hood to be withdrawn from engagement therewith. The other parts 80 of the modified form are constructed and arranged like those of the preferred form which have been fully described, and it is therefore thought that a second description of the same is unnecessary.

It is to be observed that when the hood 29 is in the position shown in Figs. 10, 11, and 12 all the effects of a ring-sight are produced, and that by sliding the hood rearwardly, so as to cause it to stand over the sight-piece, a globe-sight is produced. Therefore by constructing a gun-sight in this manner one is enabled to readily produce either an open sight, a ring-sight, or a globe-sight, and by employing the reflector he is enabled 95 to illuminate the sight-center, which becomes luminous. This illumination of the sight-center also restores the color value thereto and greatly aids in the accuracy of the sighting. In some instances it will not be necessary or desirable to use a reflector, but under certain conditions it may be found that the reflector is a most convenient and necessary accessory.

Having now fully described our invention, 105 what we claim, and desire to secure by Letters Patent, is—

1. In a gun-sight, an interchangeable sight-piece, a movable hood, and a reflector.
2. In a gun-sight, the combination with a base having guides and an interchangeable sight-piece, of a hood movable in said guides, and a reflector.
3. The combination with a gun-sight having a movable hood, of a binged reflector, and means for holding the reflector in position.
4. In a gun-sight, the combination with a base having guides, of a hood slideable in said guides, an interchangeable sight-piece, and spring-held means for locking the sight-piece in position.
5. In a gun-sight, the combination with a base having guides and a sight-piece, of a slideable hood, and means carried by the base for limiting the movement of the hood thereon.
6. In a gun-sight, the combination with a base, of a removable adjustable hood, an interchangeable sight-piece, and a reflector.
7. The combination with an elongated base and a sight-piece, of a hood shorter than the

base longitudinally and movable on the base so as to cover or uncover the sight-piece without being removed from the base.

8. In a gun-sight, the combination with a base having a concaved recess and provided with grooves, of an interchangeable sight-piece arranged on the base, a removable hood conforming to the contour of the recess and movable in the guides, and means for limiting the movement of the hood.

9. In a gun-sight, the combination with a base having a concaved recess, of an interchangeable sight-piece arranged on the base, and a movable hood conforming to the contour of the recess to form therewith a globe. 15

JOHN Y. BASSELL.
FRED C. BLENKNER.
